DIESEL ENGINE

William Fels, Fairhope, Ala., assignor to F-S-K
Manufacturing Company, Inc., Foley, Ala., a
corporation of Alabama

Application June 1, 1936, Serial No. 82,956

8 Claims. (Cl. 74—40)

This invention relates to improvements in internal combustion engines and is particularly valuable in connection with Diesel and Diesel type engines. This application is a continuation in part of my application for patent for improvements in Diesel engines, Serial No. 955, filed January 9, 1935.

The invention resides in improvements in the connections between the pistons and the crankshaft of the engine and one of the most important objects is to eliminate the direct thrust of the piston upon the crankshaft at the instant of firing of the mixture in each cylinder.

An important feature of the invention resides in the provision of a rocker fulcrumed independently of the crankshaft and pivoted to the main connecting rod in such a manner that the connecting rod and rocker are preferably in alignment, or substantially so, at the instant of ignition of the charge in the cylinder whereby the thrust of the high compression explosion is directly on the fulcrum of the rocker and is not delivered to the crankshaft which has a separate connection to the rocker.

Another important feature of the invention resides in the provision of such a connection between the cylinder and the crankshaft as to substantially eliminate the need of a fly wheel in engines of no more than three cylinders and in which the explosive effort is imparted so smoothly to the crankshaft that the drive torque is more nearly uniform than in engines of the conventional form.

Another important object of the invention is to provide a rocker so disposed and related to the crankshaft that the rocker provides an increasing lever arm for the piston thrust throughout a major part, at least, of the power stroke of the piston.

Another important feature of the invention resides in the provision of connections between the crankshaft and piston of the engine wherein the crankshaft can be disposed otherwise than substantially intersecting the extended axis of the cylinder, which permits the construction of engines of extreme compactness as regards all-over height.

Other and further features and objects of the invention will be more apparent to those skilled in the art upon a consideration of the accompanying drawing and following specification wherein are disclosed several exemplary embodiments of the invention with the understanding that such changes may be made therein as fall

within the scope of the appended claims without departing from the spirit of the invention.

In said drawing

Fig. 1 is a transverse section through the cylinder of a Diesel engine showing the piston at bottom dead center in one form of connection between the piston and the crankshaft, the drawing being largely diagrammatic;

Fig. 2 is a view of the same construction as Fig. 1 with the piston at top dead center and ready for the explosion;

Fig. 3 is a view similar to Fig. 1 showing a different arrangement of the crankshaft and rocker;

Fig. 4 illustrates a further embodiment; and Fig. 5 a still further embodiment, which construction results in maximum compactness.

Internal combustion engines are notable for developing their maximum instantaneous power over only a short portion of the piston stroke which results in extremely uneven torque as delivered by the engine unless advantage is taken of a very heavy fly wheel to absorb the maximum delivered torque of the explosion and return it

for useful work during periods when no power is delivered by the piston. This has resulted in the use of multi-cylinder engines in an endeavor to smooth out the torque curve and to overcome vibration difficulties and the size of the fly wheel

has been reduced in proportion as the number of cylinders increases and as the engine speed increases. With the advent of the Diesel engine the old troubles have returned in exaggerated form since the compression pressures in Diesel engines are many times higher than in the conventional spark ignited gasoline engine. The extremely high pressure necessary to produce spontaneous ignition results in a violent explosion with a high torque delivery over a short

portion of the stroke of the piston which tends to speed up the engine during this time resulting in an uneven delivery of power, rough operation and tremendous strains on the crankshaft and other parts. All Diesels heretofore used, therefore, had very heavy crankshafts, bearings and fly wheels.

In accordance with the present invention, the period over which the power is delivered is increased by maintaining the speed substantially uniform throughout each revolution and the torque delivery is spread out over a greater portion of the cycle so that the maximum torque peaks are eliminated and thus the size of the crankshaft and corresponding parts can be materially reduced and the fly wheel almost entire-

ly eliminated in engines having no more than three cylinders.

This will be recognized as a major step forward in the use of such engines which are highly desirable for reasons already well-known, for it enables a material reduction in weight, cost and bulk of the engines and produces a much smoother power output permitting the engine to be used in places where heretofore its use was practically prohibited.

Since most portions of the engine of the present invention are of conventional construction except in the matter of size and weight, it has been deemed sufficient to illustrate a cross section of a single cylinder with the connecting rods, crankshaft and the like diagrammatically shown since the invention deals more with the relationship of these parts to each other than to their structural features. The engine shown is of the two cycle type in order that the number of cylinders can be reduced to a minimum, although the invention, of course, is not limited to any particular mode of operation of the engine.

As shown, the cylinder 10 has mounted for reciprocation therein the piston 11 carrying the wrist pin 12 journaling the upper end of the main connection rod 13. In the construction shown in Figs. 1 and 2, the crankshaft 15 is suitably supported in bearings (not shown) and its axis intersects at right angles the extended axis of the cylinder. The throw 16 of the crank pin 17 on the crankshaft is independent of the length of stroke of the piston and can be made the same or more or less as desired.

Interposed between the main connecting rod and the crankshaft is a rocker 18 shown as having two arms 19 and 20 arranged at an angle to each other and journalled at their intersection on a fulcrum 21 intersecting at right angles the extended axis of the cylinder.

The extreme end of the arm 20 is pivoted at 22 to the free end of the main connecting rod 13 while the end of arm 19 is pivoted at 23 to one end of a secondary connecting rod 24 the opposite end of which is journalled on the crank pin 17.

The length of the connecting rod 13 and of the arm 20 of the rocker and the vertical position of the fulcrum 21 are each or all so adjusted that at top piston position, as shown in Fig. 2, the main connecting rod and its arm 20 of the rocker are in direct extended alignment while at bottom piston position they are disposed as shown in Fig. 1 wherein the rocker arm has moved through an angle somewhat greater than 90°. It will be seen that due to the disposition of the fulcrum 21 and to the length of rocker arm 20 as compared to the crank throw, the leverage exerted on the rocker increases throughout a major part of the power stroke of the piston. This is of great advantage in achieving a smooth torque application since as the piston is descending, the pressure thereabove is decreasing.

In the position of Fig. 1, at bottom dead center, the crank arm 16 and the secondary connecting rod 24 are in extended alignment while at top dead center position these same two parts are in over-lapping alignment. When, as shown in these two figures, the crankshaft axis is intersected by the extended axis of the cylinder, the second arm of the rocker is disposed at an angle of approximately 150° to the first arm in order to provide the best angles between the var-

ious parts for power transfer at different stages of the piston stroke. This second arm of the rocker must of necessity be longer than the crank arm 16 of the crankshaft in order to permit the crankshaft to make full rotation while the arm reciprocates.

Any suitable mechanical arrangement of the bearings, pivots, and the like, can be made but it is essential that the fulcrum 21 be substantial and well-supported since the explosion takes place, as shown in Fig. 2, with the connecting rod 13 and rocker arm 18 in alignment. This transfers the initial thrust of the explosion on the piston to the fulcrum, which can be short and straight and is better able to take it than the crankshaft.

The above described lever action which absorbs the initial thrust eliminates the requirement for a heavy fly wheel, for the high peak of the pressure curve is flattened to a considerable degree so that the load on the crankshaft at the upper dead center is practically zero. This converts the action of the Diesel engine to give a smoother flow of power and at the same time increases the combustion period as compared with directly connected engines so that more power is obtained from the same amount of fuel and vibration is materially reduced.

The angularity between the two arms of the rocker permits of the most desirable transfer of power between the piston and the crankshaft during the intermediate portion of the power stroke of the piston while not permitting the full thrust of the piston to be imparted to the crankshaft during the initial or high pressure part of the stroke. The angularity between the two parts of the rocker insures a quick transfer of the power of the piston to the connecting rod after the initial force of the explosion has been absorbed by the fulcrum.

The same effect as the angular relationship of the two parts of the rocker arm can be obtained with a straight rocker by offsetting the axis of the crankshaft laterally of the extended axis of the cylinder to provide the same angles between the second arm of the rocker and the secondary connecting rod, and two positions can be found which are most satisfactory, although the one shown in Fig. 3 is considered superior since it shortens the over-all width of the engine. The construction here is substantially the same as in Figs. 1 and 2 but the rocker 18' has its two arms in alignment. It rocks in the range shown by the arrows and in so doing rotates the crankshaft through the agency of the secondary connecting rod in the same manner as in the construction of Figs. 1 and 2.

Fig. 4 and 5 show two forms of the construction somewhat simpler over that of Figs. 1, 2 and 3 where, instead of a two-armed rocker, a single arm link 25 is used, fulcrumed at 26 on an axis intersecting the extended axis of the cylinder, and having the main connecting rod 27 pivoted to its end at 28. The secondary connecting rod 29 is also connected at 28 or on an axis coaxial with the pivot 28. The crankshaft 30 is offset laterally from the axis of the cylinder as in the construction of Fig. 3 and in the arrangement of Fig. 4 the crank arm 31 is in extended alignment with the secondary connecting rod 29 at top dead center whereas in the arrangement of Fig. 5 these parts are in over-lapped alignment at top dead center. These two forms require a different direction of rocking of the

link 25 as shown in the dotted arcs in those two figures.

The construction of Fig. 5 is in most cases preferable since it gives a better balanced arrangement with less over-all width and height and provides an engine well adapted for automotive use because of the low over-all height. The width is less than in the conventional horizontal type engines because the link makes much less than a half revolution.

All embodiments of the invention partake of the benefits previously enumerated and in addition they all reduce very materially the vibration of the Diesel type of engine resulting from the uneven torque delivery of the conventional form. The distribution of the torque delivery in accordance with the present constructions insures a much smoother operation and thus further permits of a reduction in the weight of moving parts and supporting structural parts.

In the form of Fig. 5 the crankshaft may be said to be between the ends of the main connecting rod and laterally disposed in respect to the extended axis of the cylinder. It should be noted that in all forms of the invention shown in the preferred embodiments above described, at top dead center the main connecting rod and its rocker are in direct alignment while at the same time the secondary connecting rod is in alignment with its crank throw on the crankshaft. However, it will be understood that while preferred embodiments have been specifically described herein, variations in the form and arrangement of parts, still affording the advantages of the increasing lever arm, are possible and are contemplated under the claims which follow.

Having thus described the invention, what is claimed as new and desired to be secured by Letters Patent is:

1. In a high compression internal combustion engine of the Diesel type, a cylinder having a piston reciprocable therein, a conventional connecting rod for said piston, a crankshaft having a throw independent of the stroke of the piston, a rocker fulcrumed on an axis intersecting the extended axis of the cylinder at right angles, the end of the connecting rod being pivoted to said rocker, the rod and rocker lengths being such that these parts are in substantial alignment at top piston position to apply the initial force of the explosion substantially solely to the said fulcrum, and a second connecting rod having a pivot to said rocker coaxial with that of the first connecting rod and having its opposite end mounted on the crank throw, said crankshaft axis being spaced a substantial distance laterally of the cylinder axis.

2. In a high compression internal combustion engine of the Diesel type, a cylinder having a piston reciprocable therein, a conventional connecting rod for said piston, a crankshaft having a throw independent of the stroke of the piston, a rocker fulcrumed on an axis intersecting the extended axis of the cylinder at right angles, the end of the connecting rod being pivoted to said rocker, and rod and rocker lengths being such that these parts are in substantial alignment at top piston position to apply the initial force of the explosion substantially solely to the said fulcrum, and a second connecting rod having a pivot to said rocker coaxial with that of the first connecting rod and having its opposite end mounted on the crank throw, said crankshaft axis being spaced a substantial dis-

tance laterally of the cylinder axis and beside the first connecting rod.

3. In a high compression internal combustion engine of the Diesel type, a cylinder having a piston reciprocable therein, a conventional connecting rod for said piston, a crankshaft having a throw independent of the stroke of the piston, a rocker fulcrumed on an axis intersecting the extended axis of the cylinder at right angles, the end of the connecting rod being pivoted to said rocker, the position of the fulcrum being so selected that with the chosen rod and rocker lengths these parts are in substantial alignment at the time of firing the charge in the cylinder whereby the initial force of the explosion is applied substantially solely to said fulcrum, a second connecting rod extending from the crank throw to a pivot coaxial with the pivot of the first connecting rod on said rocker, the crankshaft axis being so disposed laterally of the extended cylinder axis that the second connecting rod is in alignment with its crank when the main connecting rod is in alignment with the rocker.

4. In a high compression internal combustion engine of the Diesel type, a cylinder having a piston reciprocable therein, a conventional connecting rod for said piston, a crankshaft having a throw independent of the stroke of the piston, a rocker fulcrumed on an axis intersecting the extended axis of the cylinder at right angles, the end of the connecting rod being pivoted to said rocker, the position of the fulcrum being so selected that with the chosen rod and rocker lengths these parts are in substantial alignment at the time of firing the charge in the cylinder whereby the initial force of the explosion is applied substantially solely to said fulcrum, a second connecting rod extending from the crank throw to a pivot coaxial with the pivot of the first connecting rod on said rocker, the crankshaft axis being so disposed laterally of the extended cylinder axis that the second connecting rod is in overlapping relation with its crank when the main connecting rod is in alignment with the rocker.

5. In a high compression internal combustion engine of the Diesel type, a cylinder, a piston reciprocable in said cylinder, a rocker having its axis in a plane normal to the cylinder axis, a rigid connecting rod between said piston and said rocker and having a point of connection with said rocker spaced from the rocker axis, a crank whose axis is parallel to the rocker axis, and a rigid connecting rod between said rocker and crank and having a point of connection with said rocker spaced from the rocker axis a distance greater than the length of the crank throw, the points of connection of said connecting rods with said rocker being so related to each other and so spaced from the rocker axis and the crank and rocker axes being so disposed relative to each other that when the piston is at the top of its power stroke the crank is at the top of its throw and when the piston is at the bottom of its power stroke the crank is at the bottom of its throw, the rocker axis being so disposed relative to the cylinder axis and the distance between the rocker axis and the point of connection of the rocker with the connecting rod which goes to the crank being so much greater than the crank throw that the rocker provides an increasing lever arm for the piston thrust throughout a major part of the power stroke of the piston.

6. In a high compression internal combustion engine of the Diesel type, a cylinder, a piston reciprocable in said cylinder, a rocker including an

arm and having its axis in a plane normal to the cylinder axis, a rigid connecting rod between said piston and arm, a crank having its axis parallel to the rocker axis, and a rigid connecting rod between said rocker and said crank and having a point of connection with said rocker spaced from the rocker axis a distance greater than the length of the crank throw so that upon each rotation of the crank said arm swings to and fro through a certain angle, the rocker axis being so disposed relative to the cylinder axis and the distance between the rocker axis and the point of connection of the rocker with the connecting rod which goes to the crank being so much greater than the crank throw that said arm is at one limit of swing at the start of the power impulse and during the continuance of the power impulse swings away from the cylinder and the cylinder axis nearly to its other limit and to a position in which it is at an obtuse angle to the cylinder axis, said

crank being at the top of its throw when said arm is in said one limit and at the bottom of its throw when said arm is in said other limit so that the power impulse is transmitted by said arm to said crank throughout substantially a half-rotation of the crank.

5 7. An engine as specified in claim 5 wherein the said disposition of the rocker axis relative to the cylinder axis is such that the rocker axis intersects the cylinder axis and wherein the point of connection with the rocker of the connecting rod which goes to the piston is substantially on the cylinder axis at top piston.

10 8. An engine as specified in claim 6 wherein the said disposition of the rocker axis relative to the cylinder axis is such that the rocker axis intersects the cylinder axis, and wherein at top piston said arm is substantially in alignment with the connecting rod which goes to the piston.

15 20 WILLIAM FELS.
